Nathaniel Baldwin INVENTOR

UNITED STATES PATENT OFFICE

NATHANIEL BALDWIN, OF EAST MILL CREEK, UTAH

LOUD-SPEAKER ARMATURE

Application filed July 5, 1927. Serial No. 203,544.

The present invention appertains to loud speakers, and is particularly an improvement on my telephone receiver, patented May 10, 1910, No. 957,403.

5 The object is to obtain greater efficiency and more accurate reproduction by providing a stiffer armature without increasing its weight or changing its dimensions.

I attain this object by the mechanism illustrated in the accompanying drawing in which Fig. 1 is a side elevation of a part of the loud speaker containing the improved armature, Fig. 2 is a cross section of the same part along the line A B of Fig. 1 with the addition of polepieces to the parts shown in Fig. 1, Fig. 3 is a top view of the armature only, and Fig. 4 is a section of the armature along the line C D of Fig. 3.

In the several figures of the drawing the armature 1 is shown with fulcrum wires 2 attached by which it is supported within the spool 3. The U-shaped polepieces 4 and 5 inclose the spool 3 and the limbs of said polepieces act upon the ends of said armature. A connecting rod 6 communicates the movement of the armature to a diaphragm or other acoustic element.

The armature as commonly used in such devices is made of thin sheet iron or sheet steel and is more or less flexible. The movement of the end of the armature to which the connecting rod 6 is attached is transmitted without much loss to the acoustic element, but a considerable part of the movement of the other end of said armature is lost by the flexibility of the armature. In the present structure I stiffen the armature and avoid much of this loss by forming a depression 7 in the armature, or otherwise beading it. Practical use of this improved armature has proved that it increases the efficiency of the instruments in which it is used, and also improves the quality of reproduction.

I claim:

45 1. In an electromagnetic vibratory device,

an armature having a connecting element secured to one edge thereof, said armature having stiffening deformation in a substantially central zone.

2. In an electromagnetic vibratory device, 50 a thin sheet metal armature whereof the major portion of the body is substantially spherically curved to secure rigidity.

NATHANIEL BALDWIN.
